WRITING INSTRUMENT

Edgar B. Nichols, Moorestown, N. J.

Application August 19, 1944, Serial No. 550,277

8 Claims. (Cl. 120—14.5)

1

This invention relates to writing instruments, and more particularly to a mechanical pencil having a plurality of lead holders adapted to be selectively projected to writing position to present leads of different colors or grades, as desired, the present invention being an improvement over that disclosed in my Patent No. 1,730,679, granted on October 8, 1929.

In this patent, there is disclosed a mechanical pencil having a tubular casing in which are mounted a plurality of lead holders selectively movable from their respective, normally idle, non-writing positions within the casing each to a common writing position at the tapered, writing end of the casing. Movement of each individual lead holder to and from writing position is accomplished by an associated control element which extends through a suitably formed slot in a control member rotatably carried at the upper end of the casing. Each lead holder includes a lead propelling member for cooperation with a helical feed member mounted in the casing and common to all the lead propelling members. Normally, that is, when the lead holders are in their idle or non-writing positions, their lead propelling members are out of engagement with the aforementioned feed member. However, when any one of the control elements is moved in its slot to advance its lead holder to writing position, its lead propelling member is thereby brought into cooperative relation with the feed member. Subsequent rotation of the control member on the casing produces relative rotation between the lead propelling member and the helical feed member to thereby advance the lead.

With a construction such as above described, it is apparent that, when it is desired to change leads, the lead holder in writing position must first be removed to clear the path for entry of the desired lead holder into writing position and then, by another operation, the second lead holder is advanced to writing position. The pencil construction disclosed in my aforesaid patent, while it has proven very useful and popular, nevertheless has the disadvantage that it requires these two distinct operations to be performed in succession. Where, as in some cases, it has been found desirable to change leads very quickly, this constitutes an inconvenience.

The primary object of my present invention, therefore, is to provide an improved mechanical writing instrument which will not be subject to the aforementioned difficulty.

More particularly, it is an object of my present invention to provide an improved mechanical

2

pencil of the multi-lead type wherein the lead holder in writing position will be automatically returned to its idle or non-writing position upon and simultaneously with the movement of an idle lead holder into writing position.

Another object of my present invention is to provide an improved mechanical pencil as aforesaid in which the exchange of leads between the writing and non-writing positions can be accomplished with one hand and in but an instant.

Still another object of my present invention is to provide an improved mechanical pencil as set forth above the parts of which are easy to assemble and to operate.

15 A further object of my present invention is to provide an improved, multi-lead, mechanical pencil which has a large lead capacity.

Still a further object of my present invention is to provide, in a mechanical pencil of the type referred to, a plurality of lead magazines, each having its own lead holder, lead propeller and operating or feed means for the lead holder, together with a clutch device for releasably locking any one of said operating means to the pencil tip when its magazine is brought into writing position. Thus, each magazine constitutes a separate or discrete writing unit independent of the other magazines, but capable of being automatically returned to its idle, non-writing, concealed position within the pencil casing upon movement of another magazine from its idle position to the common writing position.

It is also an object of my present invention to provide an improved, multi-lead, mechanical pencil as above set forth which is comprised of a minimum number of parts, which is relatively inexpensive in cost, and which is highly efficient in use.

In accordance with my present invention, I utilize the basic design of the pencil of my above-identified patent but provide a plurality of complete writing units or magazines, each with its own lead holder, lead propelling means and helical feed member therefor, in place of only the lead holders as in my prior pencil. The individual magazines are advanced to and from writing position by control elements as in my prior pencil, but in the control member at the top of the pencil I rotatably mount a cylindrical actuating member provided with the same number of slots as in the control member, the respective slots of the control member and the actuating member being aligned for reception, by each pair of associated slots, of one of the magazine control elements. The slots of the actuating member are

50 55

so shaped relative to those of the control member that when a new lead magazine is advanced to writing position, its control element will actuate the actuating member to automatically and simultaneously quickly remove a second magazine previously in writing position and effect its return to idle position.

According to another feature of my present invention, the operating member of each magazine is formed at its lower end to cooperate with a clutch or locking element on the pencil tip. When a magazine is advanced to writing position, it becomes releasably locked to the pencil tip for cooperation therewith as a unit. The lead holders and associated lead propellers, on the other hand, are locked to the pencil casing for cooperation therewith as a second unit. When a magazine is advanced to writing position and one of said units is rotated relative to the other, the lead is caused to be moved in the lead holder and is either projected from or retracted into the pencil tip.

The novel features that I consider characteristic of my invention are set forth with particularity in the appended claims. The invention itself, however, both as to its organization and method of operation, as well as additional objects and advantages thereof, will best be understood from the following description of one embodiment thereof, when read in connection with the accompanying drawing, in which:

Figure 1 is an elevational view of one form of improved pencil according to my present invention.

Figure 2 is an enlarged, vertical, sectional view therethrough taken on the line II—II of Fig. 1, with portions broken away.

Figure 3 is a sectional view taken on the line III—III of Fig. 2.

Figure 4 is a sectional view taken on the line IV—IV Fig. 2.

Figure 5 is a fragmentary, perspective view of the magazine selector sleeve.

Figure 6 is a detail, perspective view of the automatic magazine-retracting cam.

Figure 7 is an enlarged, vertical sectional view taken through one of the retracted magazines on the line VII—VII of Fig. 2, and

Figure 8 is a detail, perspective view of the combination lead holder and ejector unit.

Referring more particularly to the drawing in which the same reference characters designate the same parts throughout, there is shown, in Fig. 1, a pencil 1 comprising a tubular casing having four parts, namely, a barrel 3, a cylindrical control portion 5, a cap 7 and a tip 9 at the writing end. A pocket clip 11 is supported on the casing between the control portion 5 and the barrel 3 in a manner more fully described hereinafter.

Within the barrel 3 is a sleeve 13 formed with a plurality of generally longitudinally extending, circumferentially distributed slots 15 terminating at their lower ends in offset slot portions 15a. The slots 15 are identical in shape to and are arranged in registry with a like number of slots 17 in the control portion 5. Each pair of slots 15, 17 has extending therethrough a control shaft 19 terminating in a control button 21 on the exterior of the control tube 5. Each shaft 19 is carried on the upper end of a rod 22 to which is secured a separate lead magazine 23 in a manner to be shortly more fully set forth, the rods 22 passing through openings 24 in an inverted bearing cup 25 supported within the expanded, lower end 26 of the sleeve 13.

The magazines 23 normally occupy an idle or non-writing position within the barrel 3, as shown by the right hand magazine in Fig. 2. By pushing any selected button 21 down in its slots 15, 17, however, the associated magazine 23 will be moved longitudinally to the writing position occupied by the left hand magazine of Fig. 2. If the advanced button at the lower end of the slots 15, 17 is then turned to the right, its shaft 19 is moved into the slot portions 15a and 17a to releasably lock the advanced magazine in writing position.

Surrounding each of the supporting rods 22 is a coil spring 27 interposed between the bearing cup 25 and the shaft 19. When a magazine is in its idle position, the associated spring 27 is expanded, as clearly seen at the right of Fig. 2, but when a magazine is moved to the writing position, its spring 27 is compressed between the shaft portion 19 and the bearing cup 25, as shown at the left of Fig. 2. Thus, if the advanced button 21 should later be moved to the left (Fig. 1) by means presently to be set forth in order to bring it into the vertical portions of the slots 15 and 17, the contracted spring 27 will force the shaft 19 upwardly thereby to return the associated magazine to idle position.

Each lead magazine includes a master cylinder 28 formed with an internal, helical groove 29 constituting a feed coil. The cylinder 28 has secured thereto at its upper end a ring 30 which is loosely confined between a pair of rings 31 brazed or otherwise suitably secured to a longitudinally split, tubular lead guide 32, whereby the cylinder 28 is rotatable on the lead guide 32. At its upper end, the lead guide 32 receives the lower end of the magazine shaft 22 to which it is locked by having its portions 32a pinched firmly about a lug 22a extending from the shaft 22. Thus, the shaft 22 and the lead guide 32 are arranged to operate as an integral unit. At its lower extremity, the lead guide 32 is formed with a reduced portion 32b which acts as a bearing for a lead or writing element 33.

The lead 33 is frictionally received in a longitudinally split, lead holding sleeve 34 which is slidable in the guide 32. The sleeve 34 is provided with projections 35 which extend through the longitudinal slot in the guide 32 and into the feed coil or helical groove 29. Slidably carried within the sleeve 34 is a lead ejecting rod 36 having a projection 37 which extends through the aligned, longitudinal slots of the sleeve 34 and the guide 32 and is also received in the feed coil 29 for cooperation therewith. By effecting relative rotation between the master cylinder 28 on the one hand and the assembly comprising the lead guide 32, the sleeve 34 and the rod 36, it will be apparent that the sleeve 34 and the rod 36 will be caused to move longitudinally within the guide 32 to thereby move the lead 33 in one direction or the other.

The casing tip 9 is conical in shape and is formed with a cylindrical extension 40 beyond a shoulder 41 which abuts the lower end of the barrel 3. Secured to the barrel 3 inside the lower extremity thereof is a locking ring 42, the upper end of the extension 40 being peened over the upper end of the ring 42 to form a bead or the like 43 which loosely locks the tip 9 around the ring 42. Thus, the tip 9 is rotatably supported on the barrel 3.

Within the tip 9 is a rubber or other suitable friction sleeve 44 constituting a friction clutch element against which the tapered, lower ex-

tremity 45 of the master cylinder is forced when a magazine is brought into writing position. This is for the purpose of releasably locking the master cylinder of a selected magazine to the tip for coaction as one unit. Since the magazine shafts 22 are locked to the barrel 3 through the shafts 19 and the control tube 5, it is apparent that the barrel 3, the tube 5, the shafts 19 and 22, the lead guide 32, the lead holder 34 and the lead ejector rod 36 will cooperate as a second unit which is rotatable relative to the first mentioned unit. Hence, by holding the tip 9 in one hand and rotating the barrel 3 and control tube 5 relative thereto, rotation will be effected between the master cylinder 28 and the parts within it to thereby propel the lead 33 in one direction or the other, depending upon the direction of relative rotation between the two units specified above.

Rotatably mounted within the sleeve 13 is a cylindrical actuating sleeve 46 by means of which automatic return of one magazine is effected from writing position to idle position while a second magazine is being advanced from idle position to writing position. The sleeve 46 rests on a reduced shoulder 47 formed on the sleeve 13, the clip 11 having a split collar 48 which is confined between the tube 5 and the reduced part of the sleeve 13. The actuating sleeve 46 is held in place by a cup 49 frictionally fitted within the upper end of the sleeve 13 and carrying an eraser 50 which is covered by the removable casing cap 7 in well known manner.

The actuating cam sleeve 46 is provided with a plurality of longitudinally extending, circumferentially distributed slots 51 corresponding in number to the number of slots 15, 17 and so arranged relative thereto that the vertical portions 52 thereof are always in alignment with the slots 15 and 17. The control shafts 19 pass through the slots 51 as well as through the slots 15 and 17 (see Figs. 2 and 3). The upper ends of the slots 51 are provided with lateral offsets 53 having cam edges 54. The lower ends of the slots 51 are formed with oppositely disposed offsets 55 which are shorter than the slot portions 15a and 17a in the tube 5 and the sleeve 13, respectively.

When the magazines 23 are all in idle position, their respective control shafts 19 are held against the upper extremities of the slots 15, 17 and 51 by the springs 27, and the actuating member 46 is in extreme clockwise position, looking down on the cap 7. When the button 21 of a selected magazine is pushed down to advance the desired magazine to writing position with its cylinder 28 in locking engagement with the friction sleeve 44, and then counter-clockwise into the slot portions 15a and 17a to releasably lock the magazine in this position, the control shaft 19 thereof engages the end of the associated slot offset 55 to also turn the member 46 counter-clockwise. The slot offsets 53 are long enough to then receive the remaining shafts 19 therein so that the idle magazines will not be disturbed.

When it is desired to change leads, the button 21 of the newly desired magazine is moved downwardly along the slots 15, 17, 51. Since the actuating sleeve 46 is now in its extreme counter-clockwise position as above described, the actuating shaft 19 of the newly selected button engages the cam edge 54, which is now interposed in its path, and forces the member 46 to rotate clockwise, whereupon the end of the slot offset 55 immediately forces the shaft 19 of the maga-

zine in writing position into alignment with the vertical portions of its slots 15, 17, 51. The associated spring 27 then quickly returns the last used magazine to its idle position, thus clearing the path for the newly selected magazine which is simultaneously brought into the writing position. This cycle is then repeated each time an exchange of magazines is effected between any two magazines one of which is in idle position and the other in writing position.

From the foregoing description, it will be apparent that I have provided an improved mechanical pencil which incorporates many advantageous features not found in prior art pencils. Although I have shown and described but a single embodiment of my invention, it will undoubtedly be apparent to those skilled in the art that many other variations thereof, as well as changes in the one described, are possible. For example, in place of the tapered end 45 of the master cylinder and cooperating friction element 44, the exterior surface of the former and the interior surface of the latter may be formed of corresponding shapes, such as square, hexagonal, etc., or they may be knurled, or formed with ribs and grooves all adapted to cooperate with each other to releasably lock the tip to the master cylinder of the magazine in writing position. Also, instead of rotatably coupling the tip 9 to the barrel 3 at the lower extremity of the barrel, the tip 9 may be made rigid with the barrel and the rotatable coupling provided somewhere along the barrel below the lower end of the sleeve 13. Furthermore, it is apparent that the slots 51 in the actuating member 46 and their offsets need not be shaped precisely as shown in the drawing, but may be otherwise suitably shaped to provide the desired action. Various other changes will, no doubt, readily suggest themselves to those skilled in the art.

I claim as my invention:

1. In a mechanical pencil, a casing, a plurality of lead magazines within said casing each movable therein to and from lead concealing and lead exposing positions and each including (1) a lead guide, (2) lead propelling means movably carried by the lead guide, and (3) an operating member for moving the lead propelling means relative to the lead guide, said operating members being non-operable to move their respectively associated lead propelling means when said magazines are in lead concealing position, manually operable means associated with said magazines for effecting simultaneous exchange of positions between a pair of said magazines one of which is in lead exposing position and the other of which is in lead concealing position, said means including an actuating member within said casing positioned beyond the lead concealing positions of said magazines, and means associated with said operating members for rendering the operating member of said other magazine operable to move its associated lead propelling means when said last named magazine is moved into lead exposing position.

2. In a mechanical pencil, a casing, a plurality of lead magazines concealed within said casing and selectively movable, one at a time, from an idle position to a writing position for projecting its lead through one end of said casing, said magazines each including (1) a lead guide, (2) lead propelling means movably carried by the lead guide, and (3) an operating member for moving the lead propelling means relative to said lead guide, said operating members being non-operable

to move their respectively associated lead propelling means when said magazines are in idle position, manually operable means for moving any one of said magazines at will to writing position, means associated with said last named means for retracting a magazine which is in writing position simultaneously with the movement of another of said magazines into writing position, said last named means including an actuating member within said casing positioned beyond the idle positions of said magazines, and means associated with said operating members for rendering the operating member of said other magazine operable to move its associated lead propelling means when said last named magazine is moved into writing position.

3. In a mechanical pencil, a casing, a plurality of lead magazines within said casing selectively movable therein one at a time from lead concealing to lead exposing position, only one of said magazines being adapted to occupy the lead exposing position while the others of said magazines simultaneously occupy lead concealing positions within said casing, each of said magazines including (1) a lead guide, (2) lead propelling means movably carried by the lead guide, and (3) an operating member for moving the lead propelling means relative to the lead guide, said operating members being non-operable to move their respectively associated lead propelling means when said magazines are in lead concealing position, means for moving any one of said magazines at will from its lead concealing position to said lead exposing position, means associated with said operating members for rendering the operating member of said any one magazine operable to move its associated lead propelling means when said last named magazine is moved into lead exposing position, and means responsive to movement of said last named magazine to lead exposing position for simultaneously returning to lead concealing position a second magazine in lead exposing position, said second named means including an actuating member within said casing positioned beyond the lead concealing positions of said magazines.

4. In a mechanical pencil, a casing, a plurality of lead magazines within said casing selectively movable therein one at a time from discrete lead concealing positions each to a common lead exposing position, only one of said magazines being adapted to occupy said common lead exposing position while the other of said magazines simultaneously occupy their respective lead concealing positions within said casing, each of said magazines including (1) a lead guide, (2) lead propelling means movably carried by the lead guide, and (3) an operating member for moving the lead propelling means relative to the lead guide, said operating members being non-operable to move their respectively associated lead propelling means when said magazines are in their respective lead concealing positions, means for moving any one of said magazines at will from its lead concealing position to said common lead exposing position, means associated with said operating members for rendering the operating member of said any one magazine operable to move its associated lead propelling means when said last named magazine is moved into said lead exposing position, and means responsive to movement of said last named magazine to said lead exposing position for simultaneously returning to its lead concealing position a second magazine in said lead exposing position, said second named

means including an actuating member within said casing positioned beyond the lead concealing positions of said magazines.

5. In a mechanical pencil, a tubular casing including a control portion adjacent one end, a tapered, tubular tip mounted on said casing at its other end, said control portion having a plurality of substantially longitudinal, circumferentially distributed slots therein, a plurality of lead magazines in said casing each movable from an idle position within said casing spaced from said control portion to a writing position in said tip and each including (1) a lead guide, (2) lead propelling means movably carried by said lead guide, (3) an operating member for moving the lead propelling means relative to the lead guide, and (4) a control element extending through a separate one of said slots, said operating members being non-operable to move their respectively associated lead propelling means when said magazines are in their idle positions, means carried by said tip adapted to cooperate with any one of said operating members when the magazine of which it is a part is advanced to writing position to render such advanced operating member operable to move its associated lead propelling means, said control elements being selectively movable in their respective slots to advance their associated magazines from said idle positions to said writing position, means for removably locking an advanced magazine in said writing position, and means within said casing control portion associated with said control elements for simultaneously unlocking an advanced magazine and effecting return thereof to its idle position upon movement of an idle magazine to said writing position.

6. A mechanical pencil according to claim 5 characterized in that said last named means is constituted by a cam device within said casing control portion.

7. A mechanical pencil according to claim 5 characterized in that said last named means is constituted by a tubular member rotatably mounted in said casing control portion, said tubular member being also provided with a like plurality of substantially longitudinally extending, circumferentially distributed slots in aligned relation with said first named slots, each of said control elements extending through a separate associated pair of said aligned slots, and characterized still further in that said tubular member slots are so shaped that movement of any one of said control elements therein to bring its magazine into locked, writing position will rotate said tubular member in one direction, and subsequent movement of a second control element in its slots to bring said second element's magazine into writing position will first rotate said tubular member in the reverse direction to release said first mentioned magazine for return to its idle position and then will rotate said tubular member again in said one direction to thereby condition said tubular member to subsequently return said second element's magazine to its idle position when another control member is operated in its slots to advance the last named member's magazine.

8. In a mechanical pencil, a tubular casing, a tapered, tubular tip rotatably carried by said casing, a plurality of lead magazines in said casing, each of said magazines including (1) a lead guide, (2) lead propelling means, and (3) an operating member rotatively associated with the lead propelling means for moving the lead propelling means relative to the lead guide upon rela-
